(57) **CLAIM**

The ornamental design for a walking assist robot as shown and described.

DESCRIPTION

FIG. 1 is a first perspective view of a walking assist robot showing the new design;

FIG. 2 is second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view taken from the encircled area 9 of FIG. 1;

The broken lines shown in the figures are for the purpose of illustrating portions of the walking assist robot and form no part of the claimed design.

1 Claim, 9 Drawing Sheets
